PAPER MESSAGE SHEET

Application filed May 6, 1930. Serial No. 450,136.

This invention relates to a message sheet of paper and the like adapted for travel through a pneumatic chute and has for its object the provision of a sheet of such construction as will facilitate the action of the air in carrying the sheet through the chute at a high rate of speed and without clogging.

It has been the practice heretofore, particularly with telephone companies, to employ a message sheet, for toll ticket purposes, of rectangular form, one end of which is folded back upon itself in inclined position and to send said message sheet from one department to another by inserting the same into the usual pneumatic conveying chute whereby air suction draws said sheet through the chute to its destination. The pneumatic chutes for this purpose are generally slot-like in cross section,—that is, they have an interior passage of relatively narrow depth approximately $\frac{1}{8}$ " to $\frac{1}{4}$ " and of a width slightly greater than that of the sheet, which is usually about $2\frac{1}{2}$ " wide. The sheet with its folded portion foremost is inserted in the chute so that its bent-back portion springs into inclined position within the narrow chute and catches the air for its travel through the chute. Throughout their length the chutes are often bent or curved in a changing course toward their destination and one of the problems in connection with the free travel of such message sheets has been to prevent their clogging at the bends of the chutes. Further difficulties have been encountered in the tendency of the sheets as heretofore used to stick against the walls of the chute and cause clogging. A cause for this sticking tendency may be found in the generation of static electricity from the frictional rub of the sheets against the walls of the chute or from the condensation of moisture upon the walls of the chute from the air therein. In any event, experience has shown that the message sheets now used do not have the rapid and certain travel through the chutes which is desired, and the aim of the present invention is to improve this condition.

In general, the object of the present invention

is to provide a sheet of such construction that it will have a greater tendency to float through the chute upon the air stream and thus have a much reduced frictional drag on the walls of the chute so as to prevent its sticking. In its preferable form, the leading and trailing corners of the folded sheet will be rounded to facilitate its travel around the bends of the chute without clogging.

Further purposes and advantages of the invention will become clearly apparent from the following detailed description taken in connection with the accompanying drawings, in which:

Fig. 1 is a longitudinal sectional view through a straight portion of a pneumatic chute showing a folded message sheet therein in position for travel in the direction of arrow a;

Fig. 2 is a transverse section of said pneumatic chute along line 2—2 of Fig. 1, showing a rear view of the message sheet;

Fig. 3 is a plan view of the message sheet flattened out;

Fig. 4 is a transverse section through line 4—4 of Fig. 3 to show the contour of the bottom of the sheet;

Fig. 5 is a view similar to Fig. 3 of a modified form of sheet; and

Fig. 6 is a transverse section along line 6—6 of Fig. 5 to show the contour of said modified form of sheet.

Referring more particularly to the drawings, 1 indicates the message sheet which may be of paper or the like, preferably about the grade and stiffness of a ledger sheet of paper. It is preferably rectangular in form with a transverse width substantially the same but just slightly less than the width of the pneumatic chute, the walls of which are indicated at 2. The interior passage through the chute 2 is slot-like in cross section, its depth being considerably shorter than its width and preferably sufficient to allow a folded back portion 4 of the sheet to spring upwardly in inclined position therein, as shown in Fig. 1. In the form we employ, the chute passage is slightly wider than $2\frac{1}{2}$ " and about $\frac{1}{4}$ " in depth.

Near the forward end of the sheet 1 a transverse score 3 is made to facilitate folding backwardly the front portion 4 of said sheet into inclined position, as shown. At each 5 end of the transverse score 3 or fold of the sheet are cut out portions 5 and 6 with rounded sides, as shown. When the sheet is folded along its score 3, the cut-out portions 5 and 6 constitute rounded corners for the leading 10 edge of the folded sheet to facilitate its non-clogging travel around bends in the chute. A further advantage of the cut out portions 5 and 6 is that they permit a balanced flow of air past each folded corner of the sheet when 15 in the chute. It is believed that the flow of air thus allowed to pass around the corner portions of the sheet assists in keeping the sheet in a position of equilibrium in floating through the chute under the force of the air 20 suction; and that the greater the stability of the sheet in its travel, the less tendency there will be for it to flutter and clog in the chute.

In addition to the foregoing means of assisting the travel of the sheets through the chute, 25 it has been found that provision of longitudinal scores such as shown at 7, 8 and 9, the indentations of which extend downwardly as shown in Fig. 4, greatly assist in the smooth travel of the sheet through the chute. These 30 indentations or scores 7, 8 and 9 permit a flow of air beneath the sheet and contribute to the floating action described. They also act as runners for the bottom of the sheet against the floor of the chute and thus lessen the generation 35 of static electricity which would tend to stick the sheet to the chute.

At the rear end of the sheet 1 another transverse score mark 10, formed by an upward indentation, is preferably provided so that the rearmost portion 11 of said sheet will bend 40 slightly downwardly as shown in Fig. 1 and thus give a slight arching effect to the rear end of the sheet in its contact with the bottom of the chute. This arrangement further 45 facilitates the passage of air beneath the sheet and reduces the frictional contact of the sheet against the bottom of the chute for the purpose above mentioned. The rear or trailing corners 12 and 13 of the sheet are also preferably rounded as shown to lessen the tendency 50 of the same to catch against the walls of the chute, particularly in passing around bends of the chute.

In the modification shown in Figs. 5 and 6, 55 the sheet 1a with its folded back portion 4a is made for a use identical with that described and the similar features thereof are correspondingly marked. In this form, however, instead of providing the longitudinal indentations, the sheet has been curled transversely 60 to a slight extent, a formation which may be easily imparted to it in the course of its manufacture. Before assuming its curled position, sheet 1a may be the same width as sheet 1 for 65 use in the same chute. It will be understood

that the longitudinal edges of sheet 1a should at all times be slightly spaced from the side walls of chute 2. This sheet 1a will be so folded for use that its convex side will be the under side against the floor of the chute. Its 70 tendency to curl upwardly at its longitudinal edges will present a relatively small contact surface for frictional drag on the floor of the chute, and moreover there will be substantially the same freedom for the air to pass 75 underneath the sheet in producing the floating travel thereof as with the first sheet described.

It has been found that a sheet constructed with one or more of the various features above 80 mentioned will travel much better through the pneumatic chute than the ordinary message sheet heretofore employed and that a sheet combining all of the various features as herein described will travel through the 85 tube with the utmost speed and certainty.

What we claim is:

1. A message sheet of paper and the like for traveling through a pneumatic chute comprising, a substantially rectangular sheet 90 with a forward portion thereof turned back upon itself along a transverse fold and having a tendency to assume an upstanding position, and cut out notches at opposite ends of said transverse fold. 95

2. A message sheet of paper and the like for traveling through a pneumatic chute comprising, a substantially rectangular sheet with a forward portion thereof turned back upon itself along a transverse fold and having a tendency to assume an upstanding position, and cut out notches with rounded sides 100 at opposite ends of said transverse fold to present rounded corners for the leading edge of said folded sheet. 105

3. A message sheet of paper and the like for traveling through a pneumatic chute comprising, a substantially rectangular sheet with a forward portion thereof turned back upon itself along a transverse fold and having a tendency to assume an upstanding position, and a plurality of downwardly indented scores in said sheet running lengthwise thereof from end to end of the sheet. 110

4. A message sheet of paper and the like for traveling through a pneumatic chute comprising, a substantially rectangular sheet with a forward portion thereof turned back upon itself along a transverse fold and having a tendency to assume an upstanding position, and cut out notches at opposite ends of said transverse fold, and a plurality of downwardly indented scores in said sheet running lengthwise thereof. 115

5. A message sheet of paper and the like for traveling through a pneumatic chute comprising, a substantially rectangular sheet with a forward portion thereof turned back upon itself along a transverse fold and having a tendency to assume an upstanding position, 120 and cut out notches at opposite ends of said transverse fold, and a plurality of downwardly indented scores in said sheet running lengthwise thereof. 125

sition, and a transverse upwardly indented score near the rear edge of said sheet to provide a downwardly bent portion thereof, said downwardly bent portion having rounded corners.

5 6. A message sheet of paper and the like for traveling through a pneumatic chute comprising, a substantially rectangular sheet with a forward portion thereof turned back upon itself along a transverse fold and having a tendency to assume an upstanding position, and cut out notches at opposite ends of said transverse fold, and a transverse upwardly indented score near the rear edge of said sheet to provide a downwardly bent portion thereof, said downwardly bent portion having rounded corners.

10 7. A message sheet of paper and the like for traveling through a pneumatic chute comprising, a substantially rectangular sheet with a forward portion thereof turned back upon itself along a transverse fold and having a tendency to assume an upstanding position, and cut out notches with rounded sides at opposite ends of said transverse fold, to present rounded corners for the leading edge of said folded sheet, a plurality of downwardly indented scores in said sheet running lengthwise thereof, and a transverse upwardly indented score near the rear edge of said sheet to provide a downwardly bent portion thereof, said downwardly bent portion having rounded corners.

15 8. A message sheet of paper and the like for traveling through a pneumatic chute comprising, a substantially rectangular sheet with a downwardly depressed portion between its lateral edges to reduce its area of contact with the bottom of said chute, the forward portion of said sheet being turned back upon itself along a transverse fold and having a tendency to assume an upstanding position, and cut out notches at opposite ends of said transverse fold.

20 45 In testimony whereof we have affixed our signatures.
